UNITED STATES PATENT OFFICE

GILBERT D. FISH, OF PELHAM, NEW YORK, ASSIGNOR TO FRANK S. LYON, OF
MINNEAPOLIS, MINNESOTA

SUSPENDED RAILWAY SWITCH

Application filed February 17, 1931. Serial No. 516,463.

Among the objects of my invention is to provide an improved switch for shifting a suspended monorail car from one track to a branch track. Another object of my invention is to provide a track switch, adapted to pass a goose neck hanger extending vertically beside the track rail between a suspended car body and overlying track wheels. Another object is to provide a switch in such 10 a situation and adapted to be shifted by rotation on a longitudinal axis. Other objects have relation to providing switching means in such a situation for the main track rail and also for a lateral guide rail, providing suitable supporting structures at the switch, providing mechanism for the application of power in operating the switch, and for locking the switch securely in its operative positions. All these objects and other 15 objects of my invention will become apparent on consideration of an example of practice in accordance with the invention which I will disclose in this specification. It will be understood that this disclosure relates 20 principally to this particular example of the invention and that its scope will be indicated in the appended claim.

Referring to the drawings: Figure 1 is a transverse section of a suspension railway structure with which my improved switch 25 may be employed; Figure 2 is a general plan view at the switch; Figure 3 is an enlarged plan view of certain details at the switch; Figure 4 is a corresponding side elevation at 30 the switch; Figure 5 is a detail section on the line 5—5 of Figure 3, looking in the direction of the arrows; Figure 6 is a section on the line 6—6 of Figure 5, looking in the direction of the arrows; Figure 7 is a section 35 on the line 7—7 of Figure 2, looking in the direction of the arrows; Figure 8 is a section on the line 8—8 of Figure 2, looking in the direction of the arrows; and Figure 9 is a section on the line 9—9 of Figure 2, looking 40 in the direction of the arrows.

Towers, such as 11 in Figure 1, stand in a row, each with a cross arm 12 supporting two longitudinal girders 13, one at each end of the cross arm. On these girders 13 are track rails 14 and on these are suspended the

cars 16 through the gooseneck hangers 15 and the doubly flanged wheels 17. Parallel with the track rails 14 are guides 18 attached to the sides of the towers 11. These guides 18 are at a level slightly below the bottom 55 of the car 16. Extending laterally from the bottom of each car 16 is projecting arm 19, carrying a guide member in engagement with the guide 18.

The foregoing description applies to 60 straight track and indicates sufficiently the construction on curves. The following description has reference more particularly to means for switching from one such main track to either of two diverging branch 65 tracks. Referring to Figure 2, the main monorail track is shown at 14 and the diverging alternative branch tracks are 14a and 14b. Between the rail 14 on one side and the rails 14a and 14b on the other side 70 lies the switch.

Between the ends 111 and 112 of the fixed supporting girders 13 extends the I section girder 113. Attached to this and branching from it so as to form a Y-like structure, there 75 is another I section girder 114. The top plate 115 overlies both I beams 113 and 114 and there is a corresponding bottom plate 116. These plates 115 and 116 are reinforced along their edges by the angles 110. The structure 80 made up of the I beams 113 and 114 and the top and bottom plates 115 and 116 is rotatably mounted on the axis indicated by the reference numeral 117. Attached to the end 85 of the girder supporting the branch rail 14a is a projecting bracket 118 (Figure 4) and the corner of the switch structure rests thereon when the switch is in the position shown in Figure 3. On the opposite side there is a similar bracket 118' (Figure 3).

Similarly, but on a smaller scale, just as the track rail is interrupted by its switch structure, so the guide rail 18 is interrupted by a switch structure consisting of the two branching guide rail sections 119 and 120 90 rigidly connected together in narrow Y form when viewed in plan and mounted to rotate on an axis 137 (Figure 9) parallel with the axis 117 of the main switch shown in Figure 3. The guide rail switch is shown in Fig- 95 ure 3. The guide rail switch is shown in Fig- 100

ure 2 in position corresponding to a connection of the main switch from the track rail 14 to the track rail 14a. When the main switch connects rail 14 to 14b, the branch 5 120 of the guide rail takes the position shown in dot and dash lines at 120'. Figure 7, which is a section on the line 7—7 of Figure 2, shows how the ends of the guide rail sections 18 and 18' are supported. The trans- 10 verse support 121 carries channels 122 and 123, the latter having its upper flange and part of its web cut away near its end, as at 124, so as to give clearance space for certain members carried on the bottom of the car. 15 When the car goes straight through from track 14 to 14b in Figure 2, the guide member carried by the arm 19 connects with the guide 18, but when the car goes from track 14 to 14a, as seen in Figure 2, the guide mem- 20 ber carried by the arm 19 connects with the guide 18'.

The guide engaging arms 19 on the cars 16 are located midway of the length of each car, as shown in Figure 2. Since the guides 25 18 are slightly below the car bottom, the car corners as at 125, 125' and 125'' can swing out and overhang the guides as shown in Figure 2. When the connection is straight from track 14, through segment 14' to track 14b 30 as seen in Figure 2, the guide rail sections 18, 119 and 18b are in strict alignment. When the connection for the track is from 14 through 14'' to 14a, the front end of the car proceeding from left to right begins to swing 35 to its right before the guide 19 does so, and until after the guide 19 passes from 18 to 119, the car must swing a little towards its left.

A supporting structure for the track rails 40 and the guides is shown in Figure 8, which is a section on the line 8—8 of Figure 2. There is an overhead transverse supporting member 126, which may be supported in any convenient manner. Depending therefrom 45 is an arm or hanger 127, and at its end this hanger 127 carries the usual longitudinal girder 13 and the overlying fixed rail end 14b. Also depending from the overhead member 126 is another hanger 127' supporting the 50 end of the girder 13' which carries the track rail 14a. Thus a clear space is provided between the two girders 13 and 13' for the passage of the gooseneck 15 when the car goes from track section 14 to track section 14b, or 55 vice versa.

The necessary length of the switch is determined by the necessary clearance for the gooseneck 15 and the maximum practicable curvature that may be given the track rail.

60 As shown in Figures 2 and 3, the switch is set to connect the track 14 with the track 14a. The switch structure is supported at three points; at one end by its projecting pin 128 attached to the switch structure at 129 and resting in the journal bearing 130 in the

end of the girder 13; and at the other end by a similar projecting pin 128' connected to the switch structure at 129' and resting in the journal bearing 130' in the end of the girder; also at this same end the switch structure is supported by its corner resting on the projecting bracket 118, as seen in Figures 3 and 4. The switch structure is cut away in part at the right hand end as viewed in Figures 3 and 4, and the journal pin 128' carries a worm wheel or worm wheel segment 131. It will be seen that this lies between the opposed aligning ends of the stationary track girder 13 and the movable switch girder 113.

Engaging the worm wheel 131 is the worm 70 132 on vertical shaft 133 driven through a pair of bevel gears 134 from the electric motor 135. Thus, by application of power from the motor 135, the switch structure comprising the I beams 113 and 114 and the top and bottom plates 115 and 116 will be rotated about its axis 117 so as to lie either in the position shown in Figure 3 with the corner resting on the bracket 118, or in the position indicated by the dotted line 115' in Figure 3 with its corner resting on the bracket 118'. In the full line position shown in Figure 3, the track rail 14'' is on top and connects between the main track rail 14 and the diverging track rail 14a. Also at this time the switch carries a track rail section 14' on its under side. When the switch structure is rotated 180 degrees so that its corner rests on the bracket 118', this puts the rail section 14'' on its under side and brings the rail section 14' up to the upper side in alignment between the stationary rail sections 14 and 14b.

In each end of the switch structure there are holes as shown at 138 and 139 in Figure 6 and in the adjacent stationary structure there is a locking pin that will lock into either hole to hold the switch definitely at either of its operative positions of adjustment.

I claim:

In combination, an overhead structure carrying a main track rail and two diverging track rails for a suspended car and also carrying corresponding side guide rails at a lower level for such a car, a switch structure rotatable about a longitudinal axis for said main and diverging track rails, and a similar co-acting switch structure for said guide rails.

Signed at New York, in the county of New York and State of New York, this third day of February, A. D. 1931.

GILBERT D. FISH.
